DESIGN FOR A GAME BOARD

George Weller, Jr., Cincinnati, Ohio

Application April 10, 1940, Serial No. 91,583

Term of patent 3½ years

To all whom it may concern:

Be it known that I, George Weller, Jr., a citizen of the United States of America, and a resident of Cincinnati, in the county of Hamilton and State of Ohio, have invented a new, original, and ornamental Design for a Game Board, of which the following is a specification, reference being made to the accompanying drawing, forming a part thereof.

The figure is a plan view of a game board showing my design.

The article, while having a third dimension, is of no appreciable or material depth or thickness.

I claim:

The ornamental design for a game board, as shown and described.

GEORGE WELLER, JR.
